GAS COMPRESSOR

Frank J. Fette, Tampa, Fla.

Application December 6, 1937, Serial No. 178,284

5 Claims. (CL 236—182)

This invention relates to pumping apparatus and particularly to gas compressors for use in air conditioning devices and in refrigeration.

It has for its primary object to provide a compressor of high efficiency and occupying only a small space, which will cause a continuous flow of gas.

Further objects include the provision of means for cooling the compressed gas, for lubrication of all moving parts, and for avoiding friction, in a simple, inexpensive, and readily assembled group of elements having a single driving element actuating a plurality of pistons of short stroke.

Other objects and advantages of the invention will appear in connection with the description of a preferred embodiment which has been selected for purposes of illustration in the accompanying drawings. It will be evident to those skilled in the art that many changes in size, form, number of parts and in the details of construction and arrangement of elements may be made without departure from the principles of the invention or sacrifice of its advantages.

In the drawings, Figure 1 is a central horizontal section with the driving cam in elevation; Fig. 2 is an end elevation with parts in section; Fig. 3 is a side elevation with parts broken away and parts in section; Fig. 4 is a horizontal section on the line IV—IV of Fig. 3; Fig. 5 is a fragmentary sectional view of the intake valve on an enlarged scale, taken on the line V—V of Fig. 6; and Fig. 6 is a fragmentary end view in elevation of the intake valve.

A drive shaft 1 to be driven by a high speed motor, is mounted in suitable bearings 2 and 3 in end members 4 and 5 which are secured, as by screws 6, to a central casing 7.

The end member 4 has formed therein a pair of cylinders 8 to receive the large ends 9 of pistons 10 and the end member 5 has formed therein smaller cylinders 11 to receive the small ends 12 of the pistons 10. These double pistons, reciprocating in the aligned cylinders 8 and 11, have their central portions adapted for sliding engagement within guideways 13 upon opposite sides of the casing section 7. These guideways have substantially parallel sides for contact with a laterally projecting portion of each piston to prevent rotation thereof, so that a pair of frusto-conical rollers 14 mounted within each piston on pivots 15 will be held with the smaller end of each roller directed toward the drive shaft 1, the vertex of the angle formed by the sides of the rollers being at the axis of the shaft 1. A cam 16 is formed upon, or secured to, the shaft 1 with the periphery of the

cam extending between the rollers 14 of each piston and having its surfaces which engage the rollers beveled to conform to the taper of the rollers.

Preferably, the surfaces of the cam will be generated by the use of milling cutters and grinding cones of the shape of the rollers 14, held in contact with the cam and reciprocated longitudinally of the shaft in simple harmonic motion with one complete reciprocation of the cutters or cones during one revolution of the cam. When formed in this manner, the cam, at every point during its rotation, will be of uniform section in every longitudinal axial plane, so that the rollers will bear upon opposite sides in line contacts radially from the shaft without binding, and since the taper of the rollers and of the cam surface at any line of mutual contact corresponds to the taper of bevel gears or to the taper of two cones having the same vertex, the rollers will run upon the cam without friction due to unequal speeds.

The rollers 14 will preferably be provided with thrust bearings 17 to resist radial pressure and the needle rollers 18 will be interposed between the rollers 14 and their pivots 15. The sides of the pistons within the casing section 7 bear against the walls of the casing at each side of the guideways 13 directly opposite the cam, and in this manner, the portion of the piston within the cylinder is relieved of side thrust against the cylinder wall.

The cylindrical portion of the central casing section 7 surrounding the shaft 1 will be filled with a lubricant which will be in contact with the cam 16, the rollers 14, the guideways 13, and all of the surfaces of the pistons which enter the lubricant chamber. Escape of the lubricant from the casing along the shaft 1 will be prevented by a suitable gland 19 which may be of the type shown in which rubber washers 20 surrounding the shaft are compressed by springs 21 against the shaft and against bronze bearing washers 22.

On the outer end of the member 4 opposite each cylinder 8 is secured a manifold 23 provided with an intake valve 24 and an exhaust valve 25. Similar manifolds 26 are secured on the outer end of the member 5 opposite the cylinders 11, these manifolds each being provided with an intake valve 27 and an exhaust or outlet valve 28. The valves 24, 25, 27, and 28, may be of any suitable type, but as shown, they are identical in construction and reversible.

Referring to Figs. 5 and 6, each valve has an element 29 provided with a plurality of ports 30 which are normally held closed by a closure ring 35

31 having guide pins 32 slidable in bushings 33 secured in a cylindrical member 34. Springs 35 surrounding the bushings 33 act to thrust the closure ring away from the member 34 against the member 29. A bolt 36 may be used to secure the members 29 and 34 together and a spring 37 interposed between the outer wall of the manifold and the connected members 29 and 34 holds one or the other of these members against its seat at the end 10 of the cylinder which it serves. The ring 38 moves inward toward the cylinder in the intake valves and outward away from the cylinder in the outlet valves.

A water jacket 38 is formed on one side of the central casing section 7. Water enters this jacket at one side 39 through the pipe 40 and leaves on the other side 41 through the pipe 42. One end wall 43 of the jacket has secured thereto a manifold 44 and the other end wall 45 has a manifold 46. Connecting these manifolds are curved tubes 47 having their ends secured within the walls 43 and 45. Each manifold 23 is connected to the manifold 44 by a pipe 48 and each manifold 46 is connected to a manifold 26 by a pipe 49.

25 Gas entering a manifold 23 through an intake pipe 50 is drawn into a cylinder 8 as the piston end 9 on its intake stroke recedes from the valve 24, and when, upon the return stroke, the pressure of the compressed gas in the cylinder becomes 30 greater than the pressure of the gas in the manifolds and in the tubes 47, 48, and 49, the valve 25 will open to allow the compressed gas to leave the cylinder 8 through the valve 25 into the outlet side of the manifold 23, whence it proceeds through the pipe 48, manifold 44, tubes 47, manifold 46, pipe 49, manifold 26, and intake valve 21 into the cylinder 11 which lies in line with the cylinder 8 in which the gas is being compressed.

As the piston 10 pauses at the end of the compression stroke in cylinder 8 and begins its return or intake stroke for that cylinder, the pressures in the assembly just enumerated will become uniform and the valves 25 and 27 will be closed by the action of their springs 35. As the intake stroke continues, gas from the intake pipe 50 will be drawn into the cylinder 8 as before, while simultaneously the gas in the opposed and smaller cylinder 11, already under partial compression, is further compressed until it is forced out through the valve 28 into the outlet side of the manifold 26 from which the outlet pipe 51 leads to a storage tank, a heat-transfer apparatus, or to other devices, depending on the uses to which the compressed gas is to be put.

55 The tubes 47 are curved to provide for such expansion or contraction as may occur because of heating by the gas or cooling by the water in the jacket, a change in the curvature compensating for greater or less length caused by the temperature changes without undue strain on their connections with the walls of the jacket.

While only two cylinders are illustrated in each end member, it will of course, be obvious in view of the present art, that as many may be provided as can be economically driven by the motor to be used to give the volume desired.

The method of assembly will also be evident, since the end member 4 is detachable from the

casing section 7, permitting the withdrawal of the pistons, cam, and drive shaft, after the flange 52 has been removed from the shaft 1.

The drawings are to be considered as purely illustrative many details being omitted, such as 5 water jackets for the cylinders, well known in the art, and manifolds or other connections between the intake and outlet pipes, such modifications being within the skill of those familiar with this art.

10 I claim:

1. A compression pump having a piston with one end of greater diameter than the other, a cylinder for the larger end of the piston having an intake valve and an outlet valve, a cylinder for 15 the smaller end of the piston having an intake valve connected by a gas passage with the outlet valve of the other cylinder, tapering rollers within the piston, an oscillating cam having tapering surfaces engaging between said rollers and arranged to cause reciprocating movement of said piston, the angle and position of the contacting surfaces being such as to cause the relative speeds of both to be equal at all points of contact.

2. A compression pump comprising a central 25 casing section, end members secured upon opposite ends of the casing and each provided with a plurality of cylinders and with a central bearing for a drive shaft, a piston for each cylinder having one end in a cylinder in one end member 30 and the other end in a cylinder in the other end member, a portion of the piston intermediate of its ends being slidably and non-rotatably mounted in the central casing section, a drive shaft journalled in the bearings in the end members, a 35 cam upon the drive shaft, spaced tapering rollers mounted within each piston and engaging opposite surfaces of the cam, the slope of the rollers and of the surfaces of the cam at every line of contact being that of two cones having the same vertex in the axis of rotation of the drive shaft.

3. In a pump, a piston mounted for reciprocation within two aligned cylinders, a guideway for the piston between the cylinders, and a cam 45 mounted for engagement within the piston to produce reciprocation thereof, the guideway being opposite the point of engagement of the cam with the piston whereby to relieve the cylinders from lateral friction due to pressure of the cam.

4. In a pump, two cylinders in alignment with each other, a piston mounted for reciprocation within said cylinders, a guideway for the piston between the cylinders, a cam mounted on a shaft whose axis is substantially parallel with the path 55 of reciprocation of the piston, the cam engaging within the piston to produce reciprocation thereof, spaced tapering rollers mounted within the piston for engagement with the opposite surfaces of the cam, the slope of the rollers and of the surfaces of the cam being such as to cause the relative speeds of both to be equal at every point in their line of contact.

5. A structure as in claim 4 having a chamber for lubricant surrounding the cam, the rollers, 60 and the central portion of the piston.

FRANK J. FETTE.
